UNITED STATES PATENT OFFICE.

FRITZ BLAU, OF BERLIN, GERMANY, ASSIGNOR, BY MESNE ASSIGNMENTS, TO GENERAL ELECTRIC COMPANY, A CORPORATION OF NEW YORK.

ELECTRIC GLOW-LAMP.

1,113,745.

Specification of Letters Patent.

Patented Oct. 13, 1914.

Application filed April 17, 1906. Serial No. 312,123.

To all whom it may concern:

Be it known that I, Dr. FRITZ BLAU, chemist, a subject of the Emperor of Austria-Hungary, and a resident of Alte Jakobstrasse 139, Berlin, Germany, have invented certain new and useful Improvements in Electric Glow-Lamps; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to improvements in electric glow lamps.

In a recent form of electric glow lamp in which the illumination is produced by the incandescence of a metallic body, it has been found necessary to provide the filaments with suspenders. The experiments made in this direction, however, have failed to give favorable results, especially in the case of incandescence bodies consisting of a material that cannot be drawn into wire for example osmium lamps. These lamps cannot be used in all positions without the filaments buckling to a very considerable degree with a consequent risk of short-circuiting. An additional defect also consists in the liability of the filaments to adhere to the suspenders, which leads to the rupture thereof when exposed to changes of temperature such as occur when switching the electric current on or off.

The present invention relates to an electric glow lamp the metallic incandescence filaments of which are held fast by suspenders, outside of or independently of the circuit, in such a manner that the changes in dimension produced by the above mentioned changes of temperature, are rendered harmless. The chief defect to which such metallic filaments are exposed, and which consists in the filaments fracturing in consequence of the temporary contraction occurring at each cooling, and also the permanent contracting which occurs as the incandescence period is prolonged, and the danger of short circuiting caused by the buckling of the heated filaments, are if not entirely obviated, at least reduced to a minimum. The means employed to effect this purpose con-

sist in making the suspender exceedingly elastic. Several ways of carrying out the invention are shown in the accompanying drawings, in which—

Figure 1 illustrates in elevation a glow lamp adapted for use in any position. Fig. 2 is a similar view of a glow lamp, adapted for use in a depending position. Figs. 3 and 4 respectively illustrate to a larger scale the method of suspending the filament and the two positions of a suspender mounted on the ends of the holder, with the current on and off.

The form of lamp which I have illustrated comprises the bulb *e* having at its base a stem through which the leading-in wires are sealed. This stem carries a central holder *d* having hubs formed thereon near the stem and at the end remote from the stem. These hubs serve as anchorages for the arms or suspenders which support the filament. In the present case the arms which support the portion of the filament near the stem also serves as part of the electrical circuit of the filament loops.

The metal filament *a* (Fig. 1) is preferably bent at a sharp angle to form the point of suspension (which can be easily done by loading the depending filament when white hot) and is hung at that point on a suspender *b* constructed of thin wire of some metal that is very elastic and very refractory for example tantalum to form a spring. The suspender may advantageously be made by twisting two or more wires together. It may also be composed of other materials, such as very hard glass (quartz glass).

The suspender *b* terminates in a hook, for the reception of the incandescence filament and is mounted in a socket *c* (Figs. 3 and 4) of platinum or other suitable material that has been previously fused into the central holder *d*. The filament is suspended from the hook by first bending down the socket so as to depress the suspender *b*, then laying the filament in the hook of the suspender and afterward raising the socket again so as to exert a pull to impart sufficient tension to the suspender *b* and filament (Fig. 4). A lamp of this kind can be used in any position.

If the lamp is intended for use in an inverted position, that is, if the filaments hang

downward, as in Fig. 2, the end of the suspender is bent into an eye through which the filament passes. In this case if the filaments should fuse on or adhere to the suspenders the elasticity of the latter would prevent the rupture of the filaments when the current was switched off, which rupture would probably occur in lamps having rigid suspenders.

10 It should be mentioned that there is no necessity for the spring suspender to be fixed in the sockets or for the spring portion and hook to be of the same material, as a hook or other fastening device for receiving the filament can be attached to the spring, which fastening device will, preferably, be made of refractory material (Fig. 3).

15 To improve the heat conducting property of the hooks and prevent them from opening, which might permit of the filaments slipping off, they may be provided with a small quantity of putty-like substance, as indicated in Fig. 3. For this purpose, I may employ the graphite and caramel cement 20 which is commonly used to secure filaments of incandescent lamps.

25 The behavior of the spring suspender is shown in Fig. 4, the full line showing the position of the spring when under the tension due to contraction of the filament on turning off the current, while the dotted line shows the position it will assume when the current is turned on and the filament relaxed.

30 The dimensions of the spring suspender which are most suitable are determined by the elasticity, softness and weight of the filaments, and also of the elasticity of the suspenders themselves. For example in the 35 case of osmium or tungsten filaments, of pointed horseshoe shape (Fig. 1) measuring 70-80 millimeters in height (the total length of the filament being therefore 140-160 mm.) and weighing about 6 milligrams, a spring 40 to be suitable should visibly bend when the hook, which is about 11 millimeters away from the point of attachment of the spring, is exposed to a pull of 10-20 milligrams, without its limit of elasticity being approximately reached, whereas a pull of $\frac{1}{10}$ gram 45 would strain the spring beyond the limit of elasticity and cause permanent flexion. The filament in turn will readily and permanently support a load of $\frac{1}{10}$ gram when 50 white hot, but this load never occurs in practice. In the foregoing example the spring 55 was stretched or put under tension to such an extent that when the filament was cut the hook moved a distance of about 2 millimeters.

60 A glow lamp of this kind acts in the following manner when in use. On switching on the current, the filament expands. The elastic suspenders therefore relax in a visible 65 manner, and return to their original posi-

tion of tension when the current is switched off. When the lamp is held in any other than a vertical dependent position, the filament undergoes an unnoticeable and quite harmless distortion, causing a change of tension in the spring and making the hook move about 1 millimeter. This movement is sufficient to exert a pull which suffices to counteract that produced by the distortion.

I claim:

1. The combination with a lamp stem and a central holder carried thereby, of a plurality of metallic filament loops mounted adjacent and substantially parallel with said holder and having their ends fastened to supports projecting perpendicularly from said holder near the stem, and straight uniformly elastic and refractory wires rigidly attached to and projecting perpendicularly from the end of said holder remote from the stem with their outer ends bent into hooks for engaging with the bends of said filament loops, said wires being flexible with respect to the supports so as to yield resiliently and longitudinally of said holder upon expansion and contraction of said filament loops.

2. The combination with a lamp stem and a central holder carried thereby, of a plurality of metallic filament loops mounted about said holder with their ends secured to rigid supports projecting from said holder near the stems and forming part of the electrical circuit of said loops, and straight uniformly resilient supports extraneous to the circuit rigidly attached to and projecting perpendicularly from the other end of said holder and engaging at their outer ends the bends of said loops, said resilient supports being yieldingly movable relative to said rigid supports by the expansion and contraction of said loops.

3. The combination with supporting means comprising a lamp stem and a central holder carried thereby, of a plurality of metallic filament loops arranged adjacent said holder and having their ends fastened to supports projecting from said holder near the stem and springs of refractory material projecting from the end of said holder remote from the stem and engaging the bends of said loops.

4. The combination with supporting means comprising a lamp stem, a central holder carried thereby and supports projecting from said holder near the stem, of a plurality of filament loops arranged adjacent said holder and having their ends fastened to said supports, and springs projecting from the end of said holder remote from the stem and engaging the bends of said loops.

5. The combination with supporting means comprising a lamp stem and a central holder carried thereby, of a plurality of metallic filament loops arranged adjacent said holder,

arms projecting from said holder near said stem and supporting the portions of said filament loops adjacent said stem, and resilient arms projecting perpendicularly from the end of said holder remote from the stem with their outer ends bent into hooks for engaging the bends of said loops.

In testimony, that I claim the foregoing as my invention, I have signed my name in presence of two subscribing witnesses.

DR. FRITZ BLAU.
